CLAIM

The ornamental design for scissors for cutting a tape, as shown and described.

DESCRIPTION

FIG. 1 is a top plan view of a scissors for cutting a tape showing my new design;
FIG. 2 is a bottom plan view thereof;
FIG. 3 is a right side elevational view thereof;
FIG. 4 is a left side elevational view thereof;
FIG. 5 is a front elevational view thereof;
FIG. 6 is a rear elevational view thereof; and,
FIG. 7 is a perspective view thereof, the blades being in an alternate position of that shown in FIG. 1.
